NUTATING DISC MOTOR

John G. Russell, Mayfield Heights, Ohio, assignor to Thompson Products, Inc., Cleveland, Ohio, a corporation of Ohio

Application November 15, 1957, Serial No. 696,772

13 Claims. (Cl. 121—69)

The present invention relates to improvements in motors operable by expansible fluids or gases, and more specifically to a nutating disc motor which is driven by an expansible fluid or gas.

In a preferred form, the present invention contemplates the provision of a nutating disc having a motor chamber for containing expansible gases, and a nutating disc mounted therein for wobbling or rotating about its axis when driven by expansible fluid. The shaft projects from the disc in a direction eccentric from the axis of rotation of the disc and is eccentrically connected to drive a power shaft rotatable coaxially with the disc. Expansible gas is directed to the motor chamber through passageways leading to the chamber above and below the disc, and the chamber is separated by a partition having a high pressure side and a low pressure side. Inlet passageways lead to a high pressure zone on the high pressure side, and exhaust passageways lead from both sides of the disc from the chamber from a low pressure zone on the low pressure side of the partition. Pressurized expansible fluid is supplied alternately to the two inlet passageways by a control valve driven by the power shaft and having a variable closure time whereby the supply of fluid is admitted for a controlled time, and thereafter cut off so that the expansible fluid will have an adiabatic expansion to complete the rotation of the disc and will thereafter flow out through the exhaust passageway. Pressurized fluid to drive the disc is delivered through the control valve having a stationery shell and a rotor secured to rotate with the power shaft. As the power shaft rotates, the valve ports supplying the alternate inlet passageways to the motor are alternately opened to rotate the disc. The length of time that each of the valve ports is opened is controlled by a variable porting slide, and when the valve port is closed, the fluid in the motor chamber will expand adiabatically to complete the rotation of the nutating disc.

The disc is arranged within its chamber to rotate in either direction without the leakage of pressure, and a reversing valve is provided for reversing the direction of rotation of the motor.

An object of the present invention is, therefore, the provision of an improved motor operable by an expansible fluid, and utilizing the principle of a nutating disc.

A further object of the invention is to provide an improved nutating disc motor employing adiabatic expansion of an expansible fluid for operating the motor.

A further object of the invention is to provide an improved control valve arrangement for regulating the flow of expansible operating fluid to a motor employing a motor chamber with a nutating disc therein.

A still further object of the invention is to provide an improved fluid flow control for a nutating disc motor wherein a variable cut-off time for the fluid delivery is obtained to thereby vary the adiabatic expansion of the gases or fluids operating the motor.

Another object of the invention is to provide an im-

2

proved nutating disc motor which can be readily reversed in direction of rotation.

A further object of the invention is to provide an improved motor employing the nutating disc principle which is operable by various types of expansible fluids or gases directly supplied to the motor or derived from mechanisms which produce expansible gases or fluids as a by-product.

Other objects and advantages will become more apparent in connection with the teachings of the principles of the invention in connection with the disclosure of the preferred embodiments thereof, in the specification, claims and drawings, in which:

Figure 1 is a vertical sectional view taken through a motor construction embodying the principles of the present invention;

Figure 2 is a horizontal sectional view taken along line II—II of Figure 1, and illustrating the internal construction of the fluid flow control valve for the motor;

Figure 3 is a fragmentary elevational view of an alternate control valve construction;

Figure 4 is a vertical sectional view of a form of the motor wherein the motor may be reversed; and,

Figure 5 is a plan view of the disc assembly of the motor.

As illustrated in Figure 1 of the drawings, the nutating disc motor embodying the principles of the present invention includes a motor housing 10 with a motor chamber 12 therein. Within the chamber there is located a flat round nutating disc 14 which is located for nutating motion within the chamber 12.

The motor chamber 12 is circular in shape and has a lower surface 16 which projects into the chamber in a conical shape and a similar upper surface 18, with the surfaces 16 and 18 forming the surfaces which mate with the upper and lower surfaces of the nutating disc 14, in order to obtain a nutating motion of the disc with the adiabatic expansion of the expansible operating fluid or gases for the motor.

40 The disc is guided in its motion by a centrally located disc supporting sphere 20. The disc has a central opening 24, in which the sphere is secured, Fig. 5. The sphere is supported to thereby support the disc in mating spherical sockets in the lower and upper surfaces 16 and 18, Fig. 1.

At one side of the motor chamber 12 and extending radially from the center thereof to the outer surface 26 of the chamber 12, is a partition 28. The partition 28 has a high pressure side 30 and an opposing low pressure side 32. The high pressure side 30 faces a high pressure zone within the pump chamber, and the low pressure side 32 faces a low pressure zone.

For supplying pressurized expansible fluid or gas to the chamber at the high pressure zone, a first expansible fluid supply inlet passageway 34 is provided above the disc. A second inlet passageway 36 is provided below the disc for the inlet of expansible fluid, and the inlets 34 and 36 communicate with the motor chamber 12 on opposite sides of the disc 14. In operation of the disc, expansible fluid or gas under pressure is directed on one side of the disc into one of the inlet passageways, such as through passageway 34, for a predetermined portion of the cycle of rotation of the disc 14, and the gas is then permitted to expand for the remainder of the cycle with an adiabatic expansion. When 180 degrees of rotation of the nutating disc has been completed, gas is admitted into the opposing passageway 36 for a predetermined portion of the cycle, and this amount of gas is permitted to expand adiabatically for the completion of the cycle.

A typical admission of gas may be of from 10 de-

grees to 45 degrees of rotation of the disc, or 90 degrees past minimum volume position.

The nutating disc motor is adapted to receive various types of gases or fluids such as air, nitrogen, products of combustion such as received from a jet engine, steam or special use products of chemical action, such as hydrazine, ethylene oxide, etc.

The disc rotates with adiabatic expansion of gas, and the expanding gas is vented from the pump chamber 12. For this purpose, the upper surface of the disc 14 is vented through an exhaust passageway 38, and the lower surface of the disc 14 is vented through an exhaust passageway 40. These exhaust passageways are always open so that the gas may freely escape when the disc is in a position to discharge the gas through them.

The upper and lower sides of the nutating disc 14 are separated on the pressure side of the partition 28 by a sliding vane 42, which is located in a deep groove which extends parallel to the disc from the edge of a slot 44 in the disc, permitting the disc to slide on the partition 28. At the base of the groove holding the vane 42 is a compression spring 46 which urges the vane tightly against the partition to prevent the escape of gas from one side of the disc to the other side with the pressure differential that occurs.

Control of gas for rotation of the disc 14 is obtained from a valve assembly 47 shown in Figures 1 and 2.

While the movement of the nutating disc 14 is herein referred to as rotation for purposes of explanation, it will be understood that a true rotation or rotation about an axis is not achieved; but instead the disc moves in a nutating movement. To transform this movement into rotation, a crank pin 48 is provided which is connected at the axial center of the nutating disc and extends coaxial therewith so as to rotate in a conical path with the nutating movement of the disc 14. This moves the upper end of the rotating crank pin about the axis of a power shaft 50. The free end of the rotating shaft 48 is connected to an offset crank end 51 of the power shaft 50, and as it rotates, the power shaft is driven in rotation in order that power may be received from the motor.

The power shaft 50 is utilized to drive the control valve 46. It will be understood that the valve may be in various positions with respect to the shaft, and as shown in its preferred form is coaxial therewith and directly driven.

The valve has an outer shell 52 provided with outlet ports 54 and 56. Expansible gas flows through the outlet ports and is controlled by a rotating core 58 of the valve which is secured to the power shaft 50.

The core is provided with an annular passageway 59 which is supplied with pressurized gas through a supply line 61. The pressurized gas flows into the annular passageway 59, and flows out of the valve core when an outlet port 63 moves into registry with one of the outlet ports in the valve shell 52.

The length of time that the gas will flow through either of the outlet ports, or in other words, the cut-off period for the flow of gas, is controlled by variable porting covers 65 and 67.

The covers 65 and 67 are corotatable and slide to cover a part of the outlet ports 54 and 56 in the valve shell 52 to thereby control the cut-off time at which time the port is closed. Thus, the position of the covers 65 and 67 will determine the amount of expandible gas fed to the motor.

An alternate form of valve is shown in Figure 3, wherein the power shaft 50 carries a cam 64. The cam 64 controls valves 72 and 74. The cam is divided into two sections 66 and 68 which are rotatably slidable relative to each other for adjustment, but which are carried on the power shaft. For adjusting the position of the cams 66 and 68, a clamping bolt 70 may be provided which is loosened for sliding the cams relative to each other, and which for this purpose, may pass through a

slot, not shown, in the upper cam 66, and be threaded into the lower cam 68. The cams are each provided with lobes with the lower cam having a valve opening lobe and the upper cam 66 being provided with a valve closing lobe. Thus, the cam 66 can be adjustably rotated to determine the length of time that the valves 72 and 74 are held open.

As illustrated in the drawings, the valve 72 connects to the passageway 34 communicating with the pump chamber above the disc 14 and the valve 74 connects to the passageway 36 communicating with the pump chamber below the disc 14. The valves are similarly constructed and, therefore, only valve 74 need be described in detail.

Valve 74 is illustrated as having an upper block 76 and a lower block 78 clamped together to form a valve chamber 80 therebetween. Within the valve chamber a poppet valve 82 is reciprocated and is shown in the open position, as lifted by the cam 64. A spring 84 urges the valve toward closed position. When the valve is open, gas is permitted to flow through a supply passageway 86 for the valve and will flow down into the inlet passageway 36 for the motor. The valves 72 and 74 are alternately opened and closed to cause rotation of the nutating disc 14.

Figure 4 illustrates a form of the motor in which the direction of rotation of the disc can be reversed. The motor includes the housing 10 with the motor chamber 12 therein. A nutating disc 88 is secured and mounted for movement on the splined supporting sphere 22, at the center of the motor chamber 12. The partition 28 is provided to separate the high pressure and low pressure zones within the pump chamber.

Nutating disc 88 carries a first spring loaded vane 90 which is located in a groove 92 on one side of the radial slot 94 in the disc to permit the disc 88 to move relative to the partition 28. A compression spring 95 urges the vane against the partition 28. On the other side of the partition, is carried a similar vane 96 located in a groove 98 in the disc on the other side of the radial slot 94. This groove also carries a compression spring 100 to urge the vane 96 against the partition.

Thus, the nutating disc 88 has its upper side sealed from its lower side on both sides of the partition 28, so that either side may be the high pressure zone, and gas will not flow from the upper side of the disc to the lower side, or from the lower to the upper side.

Passageways are provided leading into the motor chamber and these passageways are interchangeable so as to be either exhaust passageways or inlet passageways. This interchangeability is controlled by reversing valve 102, shown in Figure 4.

On the lower side of the motor housing 10, passageways 104 and 106 lead into the motor chamber 88. On the upper side passageways 108 and 110 lead into the chamber 12. Each of these passageways leads to a line connecting to the valve 102 which is provided with an exhaust outlet 112, and with pressure supply lines 114 and 116. The lines 114 and 116 connect to a control valve, such as the valve 46 in Figures 1 and 2, or the valves 72 and 74 in Figure 3. In one setting of the reversing valve 102, the passageways 108 and 104 on one side of the partition 28, are the inlet passageways, and the passageways 106 and 110 on the other side of the partition 28 are the exhaust passageways. When the reversing valve 102 is set to its other position, flow through the valve is such that passageways 106 and 110 become the inlet passageways, and passageways 104 and 108 become the exhaust passageways. This, of course, will cause the nutating disc 88 to reverse in its direction of movement, thereby reversing the direction of rotation of the power shaft 50.

In operation of the motor, such as shown in Figure 1, pressurized expandible gas is admitted to the motor chamber 12 on the pressure side 30 of the partition 28, and

above the nutating disc 14 to the inlet passageway 34. This starts the disc moving in its nutating movement, and after a short admission period, the flow of gas is cut off whereupon the gas completes an adiabatic expansion to urge the disc through the remainder of its revolution. When the disc is 180° through its movement, gas is admitted through inlet passageway 36 below the nutating disc 14 for a short period of time, and it completes an adiabatic expansion to urge the disc in its nutating movement. The expanding gas is vented out through the exhaust passageways 38 and 40.

As rotational movement of the nutating disc 14 continues, the crank pin 48 drives the power shaft 50 to provide the power for the motor. The shaft 50 also drives the moving part of a rotary valve 46 to alternately admit expanding gas to the motor in synchronism with rotation of the disc 14. The porting time, or length of time gas is admitted to the motor, is variably controlled by rotating valve port covers 65 and 67 which determine the cut-off time for the flow of gas.

Thus, it will be seen that I have provided an improved motor driven by expansible fluid or gas employing a nutating disc and obtaining the objectives and advantages hereinbefore set forth. It will be noted that power is obtained from the gas through adiabatic expansion during which time the nutating disc is driven, and power is taken therefrom.

The output of the motor is simply and readily controlled through a valve arrangement which is driven in synchronism with the motor to control the supply of gas to the opposing sides of the nutating disc. This valve control may take various forms, and completes a motor combination which is effective and can be operated on various types of expansible products, and is useful in many environments.

I have, in the drawings and specification, presented a detailed disclosure of the preferred embodiments of my invention, and it is to be understood that I do not intend to limit the invention to the specific forms disclosed, but intend to cover all modifications, changes and alternative constructions and methods falling within the scope of the principles taught by my invention.

I claim as my invention:

1. A motor adapted to be driven by an expansible fluid comprising in combination a nutating disc, a motor chamber surrounding the disc containing expansible fluid, a first and second fluid inlet passageway leading into said motor chamber above and below the disc respectively, a first and second exhaust passageway leading into said chamber above and below the disc respectively, an axially extending partition positioned across the chamber and extending through the disc to divide the chamber into a high pressure zone and a low pressure zone with the high pressure zone located at the position of the intake passageways and the low pressure zone located at the position of the exhaust passageways, means for supporting the disc within the chamber for nutating movement, a rotating crank pin connected to the disc, a power shaft coaxially located with respect to the disc and eccentrically connected to the crank pin to receive driving rotation therefrom, a rotary valve having an outer ported shell with first and second discharge ports connected to said first and second inlet passageways and having a rotating core coaxial with and driven by said power shaft, ports in said core adapted to be aligned with the ports in the valve shell, a passageway through said valve core communicating with the ports of the rotor and directing pressurized fluid thereto whereby fluid will be admitted to said first and second passageways as the valve rotates, and rotary covers for said rotary ports adjustably related to the rotating core whereby the point at which said ports close can be adjusted to determine the amount of fluid delivered to said motor chamber and the fluid will expand adiabatically for the remainder of the rotation of the disc.

2. A motor adapted to be driven by an expansible fluid comprising in combination a nutating disc, a motor chamber surrounding the disc containing expansible fluid, a first and second fluid inlet passageway leading into said motor chamber above and below the disc respectively, a first and second exhaust passageway leading into said chamber above and below the disc respectively, an axially extending partition positioned across the chamber and extending through the disc to divide the chamber into a high pressure zone and a low pressure zone with the high pressure zone located at the position of the intake passageways and the low pressure zone located at the position of the exhaust passageways, means for supporting the disc within the chamber for nutating movement, a rotating crank pin connected to the disc, a power shaft coaxially located with respect to the disc and eccentrically connected to the crank pin to receive driving rotation therefrom, a valve having fluid discharge ports connected to said first and second fluid passageways leading to the motor chamber, an inlet for said valve directing pressurized fluid through said valve discharge ports when the valve is open with said valve alternately directing fluid to said ports to operate the disc, means connected to said power shaft for driving the valve whereby the valve is driven in synchronism with the disc, and means for controlling the period of time that said valve ports are open whereby the amount of expansible fluid delivered to the chamber is controlled with the disc being driven by adiabatic expansion of the fluid after the flow of fluid is terminated.

3. A motor driven by an expansible fluid comprising a motor chamber for containing driving fluid during expansion, a nutating disc located within said chamber to be driven by expanding fluid, a driving means connected to said disc whereby movement thereof is transmitted into power, a divider in said chamber separating the chamber into a high pressure zone and a low pressure zone, a fluid inlet passageway connected to said chamber communicating with said high pressure zone, a fluid exhaust passageway connected to said chamber communicating with said low pressure zone, valve means controlling the flow of fluid into said inlet passageway whereby the fluid will cause movement of said disc, and a valve control connected to said driving means to be driven in synchronism with the movement of the disc and opening and closing the valve to supply fluid to the chamber at predetermined positions of the disc.

4. A motor driven by an expansible fluid comprising a motor chamber for containing driving fluid during expansion, a nutating disc located within said chamber to be driven by expanding fluid, a rotary shaft connected to be driven by the disc in its movement, a divider in said chamber separating the chamber into a high pressure zone and a low pressure zone, a fluid inlet passageway connected to said chamber communicating with said high pressure zone, a fluid exhaust passageway connected to said chamber communicating with said low pressure zone, and a rotary valve having a stationary port and a rotating port with an outlet port connected to supply fluid to said fluid inlet passageway, said rotary port coaxial with and connected to said rotary shaft whereby the valve operates at the speed of the disc to supply fluid thereto at the appropriate time.

5. In combination, a nutating disc adapted to be driven by an expanding fluid, a chamber shaped to contain the disc and permit expansion of the fluid to drive the disc, a divider in said chamber extending through said disc and permitting relative movement thereof and having a low pressure side facing a low pressure zone in the chamber and a high pressure side facing a high pressure zone in the chamber, a pair of fluid inlet passageways communicating with the high pressure zone in the chamber with said passageways opening on opposite sides of the disc, a pair of fluid exhaust passageways communicating with the low pressure zone in the chamber with the passage-

ways opening on opposite sides of said disc, valve means controlling the flow of fluid into said inlet passageways whereby the fluid will cause movement of said disc, and means connected to said valve means and operatively connected to said disc to open and close said valve means in timed relationship to movement of said disc for driving the disc by the flow of fluid through said inlet passageways.

6. A motor driven by an expansible fluid comprising a nutating disc adapted to be driven by an expanding fluid, a chamber shaped to contain the disc and permit expansion of the fluid to drive the disc, a divider in said chamber extending through said disc and permitting relative movement thereof and having a low pressure side facing a low pressure zone in the chamber and a high pressure side facing a high pressure zone in the chamber, a fluid inlet passageway connected to said chamber communicating with said high pressure zone, a fluid exhaust passageway connected to said chamber communicating with said low pressure zone, valve means controlling the fluid flow into said inlet passageway whereby the fluid will cause movement of said disc in a rotational nutating movement, and means for adjusting the time said valve is open relative to the movement of the disc whereby a charge of fluid will be admitted to the chamber and the valve closed before the disc has had full rotational movement and the remaining movement is obtained from the expansion of the fluid.

7. A motor driven by an expansible fluid comprising a nutating disc adapted to be driven by an expanding fluid, a chamber shaped to contain the disc and permit expansion of the fluid to drive the disc, a divider in said chamber extending through said disc and permitting relative movement thereof and having a low pressure side facing a low pressure zone in the chamber and a high pressure side facing a high pressure zone in the chamber, a fluid inlet passageway connected to said chamber communicating with said high pressure zone, a fluid exhaust passageway connected to said chamber communicating with said low pressure zone, valve means controlling the flow of fluid into said inlet passageway whereby the fluid will cause movement of said disc, a valve control connected to said driving means to be driven in synchronism with the movement of the disc and opening and closing the valve to supply fluid to the chamber at predetermined positions of the disc, and means for varying the period the valve is open relative to rotation of the disc whereby fluid is delivered to the chamber for a variable open period and will expand to drive the disc for a closed period.

8. A fluid expansion motor comprising in combination, a motor chamber adapted to receive an expansible fluid, a nutating disc mounted for rotation within the chamber to be driven by the fluid, a divider extending across the chamber and the disc to separate the chamber into a zone of low pressure and a zone of higher pressure, a fluid supply passageway communicating with the zone of higher pressure and an exhaust passageway leading from said zone of lower pressure, and means for supplying pressurized fluid to said supply passageway for only a portion of the rotation of the disc and thereafter terminating the supply of fluid whereby the fluid may adiabatically expand to transmit its power to the rotating disc.

9. The method of operating a nutating disc motor having a chamber with a disc therein and intake and discharge passageways which comprises first delivering pressurized expansible fluid to the intake passageway for only a portion of movement of the disc, and thereafter terminating the supply of fluid and permitting the fluid to expand and move the disc through the expansion period.

10. The method of operating a nutating disc fluid expansion motor having an expansion chamber with a nutating disc therein and intake and exhaust passageways which comprises intermittently delivering timed portions of pressurized fluid through the intake passageways at intervals timed with respect to the rotation of the disc, terminating each interval before the disc has completed its movement for full expansion of the fluid whereby the fluid may adiabatically expand to complete the rotation of the disc, and continually exhausting the fluid through the exhaust passageway during movement of the disc.

11. In combination, a nutating disc adapted to be driven by an expanding fluid, a chamber shaped to contain the disc and permit expansion of the fluid to drive the disc, a divider in said chamber extending through said disc and permitting relative movement thereof and having a low pressure side facing a low pressure zone in the chamber and a high pressure side facing a high pressure zone in the chamber, a pair of fluid inlet passageways communicating with the high pressure zone in the chamber with said passageways opening on opposite sides of the disc, fluid exhaust passageways means leading from the low pressure zone to conduct exhaust fluid from the chamber, valve means controlling the flow of fluid into said inlet passageways whereby the fluid will cause movement of said disc, and means connected to said valve means and operatively connected to said disc to open and close said valve means in timed relationship to movement of said disc for driving the disc by the flow of fluid through said inlet passageways.

12. A motor driven by an expansible fluid comprising a motor chamber for containing driving fluid during expansion, a disc located within said chamber to be driven by expanding fluid, a divider in said chamber separating the chamber into a high pressure zone and a low pressure zone, a fluid inlet passageway connected to said chamber communicating with said high pressure zone, a fluid exhaust passageway connected to said chamber communicating with said low pressure zone, a valve means controlling the flow of fluid into said inlet passageway whereby the fluid will cause movement of said disc, and valve operating means for alternately opening and closing the valve in timed relationship to the movement of the disc whereby a controlled amount of driving fluid will be delivered to the motor.

13. A motor driven by an expansible fluid comprising a motor chamber for containing driving fluid during expansion, a nutating disc located within said chamber to be driven by expanding fluid, a divider in said chamber separating the chamber into a high pressure zone and a low pressure zone, a fluid inlet passageway connected to said chamber communicating with said high pressure zone, a fluid exhaust passageway connected to said chamber communicating with said low pressure zone, metering means connected to deliver metered quantities of driving fluid to said inlet passageway for driving the disc, and means for intermittently operating said metering means in relation to the moving position of the disc so that the disc will be driven by the expanding fluid.
